MOTORCYCLE BODY

Alan A. Tratner, Los Angeles, Calif.
(6731 Lurline Ave., Canoga Park, Calif. 91304)

Filed Dec. 7, 1971, Ser. No. 205,777

Term of patent 14 years

Int. Cl. D12—11

U.S. Cl. D12—110

Fig. 1

Fig. 2

Fig. 3

Fig. 4

FIG. 5FIG. 6FIG. 1 is a right side elevational view of a motorcycle body showing my new design, the left side being substantially a mirror image thereof;

FIG. 2 is a top view thereof;

FIG. 3 is a front elevational view thereof;

FIG. 4 is a rear elevational view thereof;

FIG. 5 is a front perspective view thereof; and

FIG. 6 is a rear perspective view thereof.

The broken line showing of wheels is merely for illustrative purposes.

I claim:

The ornamental design for a motorcycle body, substantially as shown and described.
